CARL COERPER, OF COLOGNE, PRUSSIA, ASSIGNOR TO THE HELIOS ACTIEN-GESELLSCHAFT FÜR ELEKTRISCHES LICHT UND TELEGRAPHENBAU, OF EHRENFELD, GERMANY.

ELECTRO-DYNAMIC MACHINE.

SPECIFICATION forming part of Letters Patent No. 396,269, dated January 15, 1889.

Application filed February 15, 1888. Serial No. 264,077. (No model.) Patented in Belgium January 12, 1888, No. 80,249; in England January 14, 1888, No. 633; in France February 4, 1888, No. 188,555, and in Italy March 27, 1888, XXI, 22,992, XLV, 297.

To all whom it may concern:

Be it known that I, CARL COERPER, a subject of the King of Prussia, Emperor of Germany, residing at the city of Cologne, in the 5 Kingdom of Prussia, German Empire, have invented certain new and useful Improvements in Dynamo-Machines, (for which Letters Patent heretofore were granted to me by the governments of Belgium, dated January 12, 10 1888, No. 80,249; England, dated January 14, 1888, No. 633; France, dated February 4, 1888, No. 188,555, and Italy, dated March 27, 1888, Vol. XXI, No. 22,992, and Vol. XLV, No. 297,) of which the following is a specification.

15 In transmitting power by electricity greater or less difficulty is experienced in starting the machines, especially in such cases where the power is to be transmitted from high-speed dynamo-machines to shafts rotated at low 20 speed or at varying speeds—as, for example, in starting and running street-cars, &c.

The object of my invention is to furnish an improved construction of dynamo-machine which is especially adapted for transmitting 25 motion and power, and in which no difficulties are experienced in starting or stopping the car or other body to be driven; and the invention consists in a dynamo-machine in which one of the elements—either the field- 30 magnets or the armature—is rigidly mounted on the shaft to be driven, while the other element is loosely mounted on the shaft and checked or entirely stopped by means of a brake or other suitable checking device.

35 When the current is conducted into the dynamo, the field-magnets and armature will have a tendency to rotate in opposite direction to each other; but when one element is fixed on the shaft while the other element is 40 loose the latter will rotate alone. When the speed of rotation of the loosely-mounted element is decreased by means of the brake, it will have a tendency to impart motion to the element fixed on the shaft and thereby turn 45 the shaft. The motion imparted thereby to one element is increased when the brake is applied more firmly to the element which is mounted loosely on the axle until the latter is

held in rigid position by means of the brake, while the other element will have reached the 50 maximum speed of rotation corresponding to the current. For example, in a street-car in which one element is mounted on one of the axles and the other is loose on the axle, the loose element will have its maximum speed 55 of rotation when the car is at a standstill, and as the brake is applied to said loose element the fixed element on the axle begins to turn slowly and the car is propelled forward slowly, while as the power of the brake is increased 60 the speed of the car increases. Thus variations in the speed of the car can be obtained without requiring any change in the strength of the current.

The field-magnet and armature can also 65 both be loosely mounted on the shaft or axle, and are then provided with brake or check devices, either on the axle or independent of the axle, so that their motion can be controlled. In case one of the elements is 70 mounted directly upon the axle carrying the driving-wheels it is advisable to provide intermediate elastic or cushioned members to avoid jars or jolts. To reverse the direction of the motion of the elements, all that is necessary is to change the direction of the current to the armature. As both elements of the dynamo are in motion, but in an opposite direction to each other, the number of rotations of the dynamo can be reduced nearly 75 one-half. It is therefore possible to use comparatively small dynamos with high effect for driving shafts that do not need high speeds of rotation—such as, for instance, the axles of street-cars.

85 My improved dynamo can also be used with great success where dynamos are driven by shafts having varying speeds of rotation—as, for example, in lighting railway-trains by electricity, as in such cases the dynamo is 90 driven from one of the axles of the car.

With my improved construction the electric potential can be maintained uniformly at different speeds, one of the elements being controlled in regard to its speed of rotation 95 by a brake; or, if both the field-magnets and

armature are loosely mounted on the axle, said elements can be controlled in their speed of rotation by the brake devices.

My improved system can be used with nearly all constructions of dynamos, but is especially adapted to those types in which both the field-magnets and the armature are of ring shape. When both elements are of this shape and symmetrically arranged, considerable variations in the speed of rotation and power can be obtained by a proper adjustment of the brushes both in the field-magnets and the armature.

In the accompanying drawings, Figure 1 is a side view of a dynamo-machine mounted on the axle in the manner described, showing the brake in side view and the axle in section. Fig. 2 is a horizontal sectional view of the parts shown in Fig. 1.

20 Similar letters of reference indicate corresponding parts.

a represents the axle; *b*, the field-magnet; *c*, the armature having a hub, *d*, with a bearing-sleeve, *e*, mounted loosely on the axle.

25 *f* represents the adjustable shoes of a fixed brake, *f'*, by means of which the armature *c* can be controlled in the manner described. In case the armature is fixed and the field-magnets are mounted loosely on the axle, it 30 will be necessary to arrange the brush so as to rotate with the field-magnets.

Having thus described my invention, I claim as new and desire to secure by Letters Patent—

1. The combination, in a dynamo-machine 35 for the electrical transmission of power, of a shaft or axle, an armature and field-magnets on said shaft or axle, one of the elements of the dynamo-machine, either the armature or field-magnets, being loosely mounted on the 40 shaft or axle, and a brake or other check mechanism applied to the loosely-mounted element and capable of locking the same in a position of rest, substantially as set forth.

2. In a dynamo-machine for the electrical 45 transmission of power, the combination, with a shaft or axle, of a field-magnet mounted rigidly on said shaft or axle, an armature applied loosely on the shaft or axle, and a brake or other check mechanism applied to the 50 armature and capable of locking the same in a position of rest, substantially as set forth.

In testimony whereof I have signed my name to this specification in the presence of two subscribing witnesses.

CARL COERPER.
